UNITED STATES PATENT OFFICE

93,390

DESIGN FOR A WATCH

Jean R. Graef, Brooklyn, N. Y.

Application June 12, 1933, Serial No. 48,383

Term of patent 3½ years

To all whom it may concern:

Be it known that I, JEAN R. GRAEF, a citizen of the United States, and a resident of Brooklyn, New York, in the county of Kings and State of New York, have invented a new, original, and ornamental Design for a Watch, of which the following is a specification, reference being had to the accompanying drawing, forming part thereof.

Fig. 1 is a plan view of a watch showing my new design.

Fig. 2 is a diagrammatic perspective view with the markings omitted from the dial.

I claim:

The ornamental design for a watch, as shown and described.

In testimony whereof, I have signed my name to this specification this 10th day of June, 1933.

JEAN R. GRAEF.
